UNITED STATES PATENT OFFICE.

BURNHAM C. STICKNEY, OF ELIZABETH, NEW JERSEY, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,259,924.

Specification of Letters Patent. Patented Mar. 19, 1918.

Application filed July 9, 1913. Serial No. 777,982.

To all whom it may concern:

Be it known that I, BURNHAM C. STICKNEY, a citizen of the United States, residing in Elizabeth, in the county of Union and 5 State of New Jersey, have invented certain new and useful Improvements in Combined Type-Writing and Computing Machines, of which the following is a specification.

This invention relates to a new and improved means for preventing the carrying on in different computing zones or columns, a type of computation other than that needed for the nature of the work, and is an improvement on an application of Hans 15 Hanson, No. 626,550, filed May 11, 1911.

The particular machine shown herewith to illustrate the invention is of the Underwood-Hanson type embodying a combined typewriting and computing mechanism. In 20 addition the numeral keys set individuals of a nest of pins by a method of cross-selection, so that the pins set correspond to the values of the numeral keys struck and to the denominational columns in which the pins 25 are set. For subtraction, the subtracting mechanism is adjusted so as to set the pins according to the complements of the numeral keys struck, using nine as a base or measure in this decimal system. In either 30 case, the members bearing the pins always rotate computing wheels in the same direction so as to run up either an adding or a subtracting computation.

Other features necessary to a normal subtracting operation in this type of machine, such as the setting of "9" pins and the giving of an extra step of rotation to the units or cents wheel, are also taken care of.

It might happen in such a machine where 40 the operative depends on his memory for changing from one type of computation to another, that he would forget to shift at the proper time and thus add when he should subtract. Hence the object of this 45 invention, which is to warn the operative when a subtracting zone is reached and to prevent the operation of the numeral keys until the mechanism has been set for subtraction.

50 In carrying out this object, the mechanism

is so set that when about to typewrite in a computing zone or column in which it is necessary to subtract in the particular type of work being done, a locking bar will be automatically brought into play to lock all 55 of the numeral keys against operation and throw up a warning sign showing that it is necessary at this point to subtract. The numeral keys will be locked against further actuation, and thus the computing mechanism be rendered incapable of operation 60 until the subtraction key is actuated to set the mechanism for subtraction.

In passing from this computing zone or column in which a subtracting operation 65 is carried on, there is also an automatic return to an adding condition of the computing mechanism. Means is provided to throw the computing mechanism back to a condition to add as soon as any tabulating 70 key is struck, to bring the traveling carriage of the typewriting mechanism to the next computing zone or column, which may be an adding one.

Other features and advantages will here- 75 inafter appear.

In the accompanying drawings:

Figure 1 is a vertical section taken from front to rear of the machine, with parts omitted for the sake of simplicity and showing the mechanism in a normal inactive condition with the lock for the numeral keys dormant or ineffective and with the computing mechanism set for addition.

Fig. 2 is a detail view of the tripping 85 mechanism which controls the release of a latch for the automatically-acting lock which prevents an actuation of the numeral keys in a subtracting zone or column until after the subtraction setting key has been 90 actuated. The parts are shown with the trip just being actuated to release the latch.

Fig. 3 is a view of certain of the parts shown in Fig. 2, showing, however, the typewriter carriage moving in the return direction and passing idly by the tripping mechanism.

Fig. 4 is a skeleton detail view in elevation, showing the lock for the numeral keys in the act of being released after having 100

come into play in a subtracting zone or column by an actuation of the subtraction setting key, which at the same time adjusts the pin-setting mechanism for subtraction setting.

Fig. 5 is a detail view of certain of the parts shown in Fig. 4, and showing the subtraction setting mechanism in the act of being released by the actuation of a tabulating key so that it may return to its normal adding condition.

Fig. 6 is a rear view in elevation partly broken away to show the underlying structure and showing the parts in a normal adding condition without the numeral key lock being in play.

Fig. 7 is a skeleton top plan view with parts removed to simplify the showing and illustrating the relation of the subtraction key and the tabulating keys to the locking and releasing mechanisms.

Fig. 8 is a detail top plan view of the pin-setting linkages illustrating the adding and subtracting arms and their relation to the different linkages.

Fig. 9 is a detail vertical section of the pin-setting mechanism illustrating the means for adjusting the same for a subtracting action.

Referring more particularly to the separate parts of this invention as embodied in the form shown in the drawings, 1 indicates numeral keys and 2 alphabet keys, which are mounted on key-levers 3 arranged to rock bell cranks 4 and thus swing type-bars 5 up rearwardly against the front side of a platen 6 mounted to rotate on a carriage 7. The carriage 7 has a step-by-step movement controlled at the actuation of each of the keys by an escapement mechanism indicated in general at 8. This escapement mechanism includes a rack bar 9 movably mounted on the carriage 7 by means of a pair of arms 10 pivoted to the carriage. The rack bar 9 meshes detachably with a pinion 11 mounted on the same shaft as a ratchet wheel 12, which is controlled in its movement by dogs 13, the latter being oscillated at the actuation of any of the numeral or alphabet keys by means of a universal bar 14, which in turn is actuated by a heel 15 formed on each of the type-bars 5.

In addition to the step-by-step movement of the carriage 7, provision is made for a jump or tabulating movement. For this purpose, there are provided tabulating keys 15 mounted on key-levers 16, which are pivoted intermediate their ends on a rod 16 and support thrust bars or plungers 17 at their rear ends. These thrust bars 17 are arranged to be projected by their associated keys into the path of tappers or stops 18 adjustably mounted on a rack 19 carried by the carriage 7. When any one of the tabu-

lating keys 15 is depressed and thus when any one of the thrust bars 17 is raised, the carriage 7 will be disconnected from the escapement mechanism 8 by means of a universal lever 20, which engages in a series of notches 21 provided in the plungers 17. This lever 20 when rocked by one of the plungers 17, pulls down on a link 22, which rocks a lever 23 carrying at its front end a roller 24, which is arranged to lift the rack bar 9 out of mesh with the pinion 11.

In addition to actuating the type action of the typewriting mechanism, the numeral keys 1 are arranged to control a pin-setting mechanism indicated in general at 25, which sets pins 26 mounted on a series of bars 27, which are provided at their front ends with racks 28 engaging with pinions 29 for dial or computing wheels 30 having numbers on their peripheries arranged to be exhibited through a sight opening 31 in the casing 32 of the computing mechanism.

In order that any one of the pins 26 on the bars 27 may be set, the bar carrying the pin must be raised above its fellows, as the pin-setting mechanism 25 has but a limited sphere of action. For this purpose, there is provided on the carriage, a tappet 33, which, during a traveling movement of the carriage, comes successively into engagement with individuals of a series of jacks 34, one for each of the computing wheels 30. These jacks are pivoted intermediate their ends, so that when engaged by the tappet 33, they will be rocked to depress thrust links 35, which are connected to transposition linkages 36, which in turn raise the rack bars 27. The linkages 36 invert the order of action of the rack bars 27 from that of the jacks 34, so that the progressive movement of the carriage, which travels from right to left, may correspond to the progressive action of the computing, which travels from left to right of the computing wheels 30.

The pin-setting mechanism 25 not only sets the pins 26 for addition but is also capable of setting them for subtraction. The particular arrangement and action of the pin-setting mechanism will now be described.

Referring to Figs. 1, 8 and 9, it will be seen that each of the numeral keys 1 is provided with a thrust link 37, which is arranged to engage an arm 38 on a rock shaft 39, there being one of these arms and one of these rock shafts for each of the numeral keys from "1" to "9."

Mounted on the shafts 39, there are provided addition arms 1^A, 2^A, 3^A, 4^A, 5^A, 6^A, 7^A, 8^A and 9^A. Each of these arms is arranged to engage, when the associated arm 38 is depressed, with the corresponding one of a series of wrist-pins, 1^W, 2^W, 3^W, 4^W, 5^W, 6^W, 7^W, 8^W and 9^W on a series of pin-setting link-

ages 1^L, 2^L, 3^L, 4^L, 5^L, 6^L, 7^L, 8^L and 9^L. Each of these linkages, as will be seen by reference to Fig. 9, comprises an upper reach 40, and a lower reach 41 parallel to the upper reach 40 and connected thereto by a pair of bell crank levers 42, so that the motion of the reaches 40 and 41 will always be parallel. These linkages are held normally in close collapse with the lower reach 41 raised, by means of one or more springs 44. When, however, one of the rock shafts 39 is rotated by the engagement of one of the thrust links 37 with the associated arm 38, then the lower reach 41 will be depressed to engage the opposite pin 26 on the particular bar 27 which happens to be raised by the action of the tappet 33 engaging one of the jacks 34. That is to say, the pin corresponding to the particular numeral key struck will be set on the particular denominational bar corresponding to the denominational column being written in on the work-sheet on the platen.

In order to subtract, the pin-setting mechanism is adjusted to set pins corresponding to the complements of the numeral keys struck instead of their direct values. That is to say, all of the rock shafts 39 are mounted to slide in a frame 45 and can be shifted to remove all of the arms 1^A, 2^A, 3^A, 4^A, 5AS, 6^A, 7^A, 8^A and 9^A out of engagement with the wrist pins 1^W, 2^W, 3^W, 4^W, 5^W, 6^W, 7^W, 8^W and 9^W, at the same time moving a series of arms 1^S, 2^S, 3^S, 4^S, 5AS, 6^S, 7^S and 8^S into engagement with wrist pins 1^P, 2^P, 3^P, 4^P, 5^P, 6^P, 7^P and 8^P on the pin-setting linkages 8^L, 7^L, 6^L, 5^L, 4^L, 3^L, 2^L and 1^L, respectively. The arms 1^S, 2^S, 3^S, 4^S, 5AS, 6^S, 7^S and 8^S are on the shafts 39 which correspond to their number and the numbers of the numeral keys which actuates these shafts. It will be noted in passing that the arm 5AS corresponding to the numeral key "5" is used for both addition and subtraction, inasmuch as it lies between the 5^L and 4^L linkages which correspond to the adding of five and the subtracting of five, respectively. There is no subtraction arm provided for the "9" set as the complement of nine is zero in this system.

In addition to the arms just mentioned, each of the shafts 39 carries a restoring arm indicated successively to correspond with the accordant numeral keys 1^R, 2^R, 3^R, 4^R, 5^R, 6^R, 7^R, 8^R and 9^R, which at the shifting of the rock shafts 39 in the frame 45, are brought into engagement with wrist pins RW on a "9" pin restoring linkage 46, acting similarly to the linkages 1^L, 2^L, 3^L, 4^L, 5^L, 6^L, 7^L and 8^L, except that it restores the "9" pins which have been previously set up, as will be described hereinafter.

For the purpose of setting for subtraction, there is provided a subtraction rod 49 (Fig.

1), which may be moved against the tension of a spring 48 to oscillate a lever 53 secured to a rock shaft 54 and engaging a shifter bar 56 pivoted at opposite ends of its upper edge as at 57. The shifter bar 56 extends into a series of aligned slots 58 provided in each of the pin-setting rock shafts 39, so that when the subtraction rod 49 is thrust rearwardly, it will swing the lower edge of the shifter bar 56 forwardly and thus shift all of the rock shafts 39 forwardly to a position such that the arms 1^A, 2^A, 3^A, 4^A, 5AS, 6^A, 7^A, 8^A and 9^A are shifted out of engagement with their wrist pins 1^W, 2^W, 3^W, 4^W, 5^W, 6^W, 7^W, 8^W and 9^W, and at the same time the subtraction arms 1^S, 2^S, 3^S, 4^S, 5AS, 6^S, 7^S and 8^S are shifted into engagement with the corresponding wrist pins 1^P, 2^P, 3^P, 4^P, 5^P, 6^P, 7^P and 8^P. This shifting also brings the pin-restoring arms 1^R, 2^R, 3^R, etc., into engagement with the wrist pins RW on the pin-restoring linkage 46. Such an action changes the pin-setting mechanism from a state in which it will set pins corresponding to the numeral keys actuated, to the opposite state in which it will set pins corresponding to the complements of the numeral keys struck, using one less than the exchange value, that is nine, as the base or complete number.

As has been stated above, it is necessary at this time to set all of the "9" pins so that if no number is subtracted in any particular denominational column, the computing wheel will have a chance to rotate a complete revolution. For this purpose, each of the "9" pins is provided with a reduced portion or neck having shoulders on opposite sides thereof, between which engages one end of a lever 59 pivotally mounted intermediate its ends on the associated pin-bar, as at 60, and projecting rearwardly to a point underlying the lower reach 61 of the pin-restoring linkage 46. That is to say, there is one of these levers 59 for each of the pin-bars 27, engaging the "9" pin thereof, so as to be capable of setting it and unsetting it.

Secured also to the rock shaft 54, there is provided a bail 62, which overlies all of the "9" pin levers 59 forwardly of their pivots and is swung down at an actuation of the subtraction rod 49 to set all of the "9" pins. To do this the rack bars must be raised at the same time that the bail 62 is swung downwardly. The rack bars are raised concomitantly by a bail 63 universal thereto and shown in the form of a bell crank pivotally mounted at 64 and having a projecting arm 65 connected to the subtraction rod 49, so that when the latter is forced rearwardly this bell-crank bail will be rocked to raise all of the pin-bearing rack bars.

In order to accomplish the shifting of the subtraction rod 49, there is provided a subtraction key 66, which, as will be seen by reference to Fig. 7, extends transversely of the machine and is of considerable length, so that it can be readily actuated by the operative. The key 66 is supported by a pair of spaced arms 67, which are pivotally mounted on the rod 16^a on which the tabulating keys are also pivoted. It will be seen that the subtraction key 66 and its arms 67 avoid interference with the tabulating keys by passing around the same.

Secured to the subtraction key 66 by an extension 68, there is provided a thrust link 69 having a cam 70 (Figs. 4 and 7), which cam is arranged to engage a pin 71 on the subtraction rod 49 and force the subtraction rod rearwardly to set the mechanism for subtraction. The thrust rod 69 may be guided for motion in a slot 72 in a portion of the frame and may also be limited in its motion by a pin 73 thereon engaging the top of the frame.

It will thus be seen that when the subtraction key is depressed, inasmuch as the thrust link 69 is held against transverse movement, it will cam the subtraction rod 49 rearwardly and actuate the various mechanisms necessary to the changing from an accumulation for addition to an accumulation for subtraction. The subtraction key 66 is returned to its normal raised position by a spring 74 engaging one of the arms 35 therefor.

In order to avoid the operative forgetting to actuate the subtraction key 66 when it is necessary to subtract, there is provided a numeral key lock 75, which is shown in the form of a bail secured to a rock shaft 103 and having a transverse bar 76 arranged to engage under a series of hooks 77, one of which is provided on each of the numeral keys. This lock is provided with a spring 78, which normally tends to draw the transverse locking bar 76 beneath the hooks 77 so as to prevent the actuation of the numeral keys. This action of the spring 78 to move the lock 75 to its effective position is prevented however by a latch 79 provided on a rock shaft 80. The rock shaft 80 is provided with an arm 81 which is normally held by a spring 82 in a position to cause the latch 79 to project in front of the lock 75 and thus prevent its movement to a locking position under the pull of the spring 78.

In order to release the latch 79 and thus bring about a locking movement of the lock 75 when a computing zone or column is reached in which it is desired to subtract, there is provided a trip 83, which is connected to be actuated from the carriage. The trip 83 is connected by a link 84 to the arm 81, so as to move the latch 79 to a releasing position, and is shown in the form of

a lever pivoted intermediate its ends and having a one-way movable camming dog 85, which may be engaged by suitably formed and arranged tappets, such as the tappets 18, which may or may not be used also for determining the position of the typewriter carriage in a tabulating action.

The tappets 18, as will be seen by reference to Fig. 1, have a long leg 86 and a short leg 87. The tappets can be readily reversed in the rack 19, so that either the long leg or the short leg is undermost. When the long leg is undermost, the tappet is in a position to determine a subtracting zone or column when the carriage arrives at a position such that this tappet will come into engagement with the trip 83. When the short leg of the tappet is lowermost, then the tappet 18 will be ineffective to control a subtracting zone or column, but may merely act as a stop to determine the position of a computing zone or column.

The camming dog 85 is positively stopped from movement on one side and yieldingly held against movement on the other side by a spring, so that during a movement of the carriage 7 in a step-by-step direction, as illustrated in Fig. 2, the trip 83 will be actuated, and further so that during a return movement of the carriage, as in Fig. 3, the subtraction tappets 18 will pass idly by without rocking the trip 83.

When the locking bar 76 is brought into play, the operative is at the same time notified that a subtraction column is reached. This is accomplished by providing an extension 88 on the lock 75, which has a tab 89 with the inscription "Sub." thereon, which tab is projected out through a slot 90 in the frame of the machine to a position where it will be readily seen by the operative.

When the subtraction key 66 is actuated it not only sets the computing mechanism for subtraction but also moves the lock 75 from engagement with the hooks 77, so that the numeral keys can be actuated to perform a subtracting operation. For this purpose, there is secured to one of the arms 67 of the subtraction key 66, a link 101, which has a lost motion or pin-and-slot connection with an arm 102 secured to the rock shaft 103 to which the lock 75 is also secured. It is manifest that when the subtraction key 66 is actuated, it will swing the lock 75 rearwardly withdrawing the locking bar 76 from the hooks 77, at the same time withdrawing the warning tab from view.

When a subtracting action has been completed, it is desirable to return the computing mechanism automatically to an adding state, as the next computing zone or column may be an adding one and it is not desired to depend on the memory of the operative

to effect the change. When the pin-setting mechanism 25 was adjusted for subtraction, a latch 92 was forced up automatically by a spring 93 to such a position that it engaged 5 under the shifter bar 56 and held it in a subtracting condition against the tension of a spring 94. Now, then, when a subtraction column is ended with, the operative naturally strikes one of the tabulating keys 15 10 to bring the carriage 7 to the next computing zone or column.

In actuating any one of the tabulating keys, the levers 16 thereof will come into engagement with a rail or bar 95, which underlies all of the tabulating key-levers 16, as will be seen by reference to Fig. 7, and is universal thereto. This universal rail or bar 95 is supported by a pair of arms 96 secured to a rock shaft 97. An arm 98 is also secured to the rock shaft 97 so as to be swung thereby, which arm is connected by a link 99 to an arm 100 connected to rock the latch 92, which holds the pin-setting mechanism 25 in a subtracting condition.

It will thus be seen that when any of the tabulating keys is actuated to move the carriage 7 to the next computing zone or column, the pin-setting mechanism will be automatically returned to its adding state.

The numbers indexed or set up by the pins for either addition or subtraction are run up on the computing wheels 30 in the usual manner by a cross bar 104 of a general operator 105 moving forwardly to engage 30 the set pins and thus advance the racks 27 amounts corresponding to the pins set theron, which racks in turn rotate the computing wheels 30. The general operator 105 may be actuated in any usual manner, as by 35 being provided with a rack 106 driven by a pinion 107, which in turn is driven by a segment 108 connected to be oscillated by a handle 109. Tens-carrying for the computing wheels 30 may be carried on in the usual 40 manner on the return stroke of the general operator, by means of tens-carrying mechanism indicated in general at 110.

In the operation of the device, the tappets or stops 18 are placed on the rack 19 at 45 points where it is desired to have the different computing zones or columns. When it is desired merely to add, the longer leg 86 of the tappet for the particular computing zone or column is placed uppermost, so that it 50 will escape the trip 83 when the carriage passes along to bring it thereover. At such points, however, where it is desired to have subtracting zones or columns, the tappets 18 are reversed in their position with the longer 55 leg 86 undermost, so that when it comes into superposed relation with respect to the dog 85 on the trip 83, it will rock the same to bring about a locking of the numeral keys.

We will assume for the purpose of illustration, that the first computing zone or

column is an adding one; the second a subtracting one, and the third an adding one. The carriage 7 is first brought to the extreme right and a tabulating key 15 struck to bring the carriage to the initial computing zone or column. The tappet 18 located for this purpose will bring the carriage to a stop at the desired point, but will not touch or move the trip 83, so that the numeral keys will be free from obstruction. The numeral 75 keys 1 can then be actuated to write the number on the work-sheet carried by the carriage and also to set it up in the nest of pins, from whence it may be run up in the usual manner by an actuation of the general 80 operator so that it will be exhibited in the computing wheels 30.

After the general operator and the parts actuated thereby have been returned to their normal positions, the mechanism is again in 85 condition for another computation. One of the tabulating keys 15 is again actuated but this time as the carriage 7 moves along, one of the tappets 18 with the longer leg 86 undermost will engage the dog 85 before the carriage comes to rest and rock the trip 83 so as to move the latch 79 to a releasing position. This enables the operation of the spring 78 to bring the locking bar 76 beneath the hook 77, at the same time exhibiting the "Sub." tab at the top of the machine.

If the operative does not notice the "Sub." tab coming out, he will be prevented from actuating the numeral keys by the locking bar 76, so that he will realize he is in a subtracting zone or column and that it is necessary to actuate the subtraction key 66 in order to release the lock 75 and permit a further actuation of the numeral keys. The operative then presses on the subtraction key 105 66, which, through the intermediary of the link 101 and the arm 102, rocks the shaft 103, so as to withdraw the lock 75 from engagement with the hooks 77 against the tension of the spring 78. The tappet having 110 in the meanwhile passed beyond the dog 85 will permit the spring 82 to return the latch 79 to its effective position, such that it will hold the lock 75 in its ineffective position; the latch 79 having in the meantime rested 115 on one of the side arms of the lock 75.

The actuation of the subtraction key 66 in addition to releasing the numeral keys, of course shifted all of the pin-bearing rack bars 27 temporarily to a raised position so 120 that the universal bail 62, which at the same time was swung downwardly, could set all of the "9" pins. The rock shafts 39 were also shifted to their subtracting position and the shifter bar 56 locked in its subtracting 125 position by the latch 92. The numeral keys 2 are then free to be actuated to write the numbers to be subtracted on the work-sheet, and at the same time set up in the nest of pins, the pins corresponding to the comple- 130

ments of these numbers. When all of the digits of the number to be computed are thus indexed or set up, the general operator can be again actuated to run up this 5 number in the computing wheels.

When the general operator is returned to normal position, the parts will then be in condition for a further computing action. To bring the carriage 7 to the next computing zone or column, the operative naturally strikes one of the tabulating keys 15, whereby the carriage is not only jumped to the new zone, but in the example given, the computing mechanism will be returned to its 10 normal adding state. That is to say, the tabulating key 16 which is actuated, will depress the universal bar or rod 95 to rock the shaft 97 and thus draw up on the link 99 to release the latch 92, permitting the spring 15 20 94 to return the rock shafts 39 and the pin-setting linkages to their addition setting relation.

Of course if the next computing zone or column should have happened to be a subtracting one instead of an adding one, the trip 83 would again be actuated to bring the lock 75 once more to its effective position to prevent an actuation of the numeral keys 2. That is to say, at the actuation of any of 25 30 the tabulating keys, the pin-setting mechanism is automatically returned to its adding state but if the next column should happen to be a subtracting one, the locking mechanism for the numeral keys is brought immediately into play, so that the operative would have to actuate the subtraction key 66 for every subtracting column desired.

Variations may be resorted to within the scope of the invention and portions of the 40 improvements may be used without others.

Having thus described my invention, I claim:

1. In a computing machine adapted to compute in different zones, the combination 45 with computing mechanism, of a traveling element to determine the zones in which computation may take place, means, under the control of the operative, for changing the state of the computing mechanism at 50 will, at any computing zone, and means controlled by said traveling element on reaching a predetermined zone for indicating to the operative that a change in state must be made.
2. In a computing machine adapted to compute in different zones, the combination 55 with computing mechanism, of a zone-controller for determining different zones in which computation may take place, means under the control of the operative for controlling the state of the computing mechanism in any zone, and means brought into 60 action by the zone-controller to oblige the operative when writing in any predetermined computing zone to accord the char-

acter of computation with that particular zone.

3. A computing machine having, in combination, computing mechanism, numeral keys which may print in different zones or 70 columns, and also control said computing mechanism, a state-controlling mechanism for said computing mechanism, and means for obliging the operative to accord the state of said computing mechanism with certain predetermined zones or columns in which printing is to take place. 75

4. The combination with a computing mechanism, of a series of numeral keys for actuating said computing mechanism, a 80 traveling carriage, a series of tappets carried by said carriage, certain of said tappets being of different form from certain others of said tappets and corresponding to different types of computation to be carried on 85 by said computing mechanism at different points in the travel of said carriage, and means actuated automatically by the tappets having a certain form at certain predetermined points in the travel of said carriage, 90 for warning the operative that a different type of computation is necessary at said predetermined points from that just previously carried out by said computing mechanism. 95

5. The combination with a computing mechanism, of a series of numeral keys for actuating said computing mechanism, a traveling carriage, a series of tappets carried by said carriage, certain of said tappets being different from certain others of said 100 tappets and corresponding to different types of computation to be carried on by said computing mechanism at different points in the travel of said carriage, and means actuated automatically by certain of said tappets for locking said numeral keys against actuation at certain predetermined points in the travel of said carriage corresponding to a change in the type of computation to be carried out by said computing mechanism. 105

6. The combination with a computing mechanism capable of existing under a plurality of states corresponding to different types of computation, of a key for controlling the states of said computing mechanism, a series of numeral keys for controlling the computations of said computing mechanism, means operable automatically prior to the actuation of said state-controlling key, for locking said numeral keys, and means operated automatically consequent upon the actuation of said state-controlling key to release said locking means. 110 115

7. The combination with a computing mechanism capable of existing under a plurality of states corresponding to different types of computation, of a series of numeral keys for controlling the action of said computing mechanism, locking means for said numeral keys, a state-controlling key for 120 125

said computing mechanism for changing from one type of computation to another, a traveling element, automatically actuated means for bringing said locking means into action to lock said numeral keys at different predetermined points in the travel of said element corresponding to the requirements of different types of computation by said computing mechanism, and connections for releasing said locking means at the actuation of said state-controlling key.

8. The combination with a computing mechanism capable of existing under a plurality of corresponding states to different types of computation, of a series of numeral keys for controlling the action of said computing mechanism, means tending to normally lock said numeral keys, a state-controlling key for varying the type of computation carried on by said computing mechanism, a traveling element, a latch normally preventing the actuation of said locking means, automatically-operated means for releasing said latch at different predetermined points in the travel of said traveling element, and connections from said state-controlling key for releasing said locking means after the same has been brought into play by said traveling element on an actuation of said state-controlling key.

9. In a combined typewriting and computing machine, the combination with computing mechanism and typewriter numeral keys controlling said computing mechanism, of a traveling carriage to determine the zones in which computation may take place, means, under the control of the operative, for changing the state of the computing mechanism at will, in any computing zone, means for locking said numeral keys when a computing zone is reached in which a change of state must be made, and indicating means for indicating to the operative why said keys are locked.

10. The combination with a computing mechanism, of a traveling element, means for determining the different computing zones or columns on traveling movements of said traveling element, a series of numeral keys for actuating said computing mechanism, locking means for said numeral keys, actuating means for said locking means operated automatically during the travel of said traveling element from certain computing zones or columns to certain other computing zones or columns, said computing mechanism being capable of existing under a plurality of different states corresponding to different types of computation, a key for controlling the change in state of said computing mechanism, and connections for releasing said locking means at an actuation of said state-controlling key.

11. The combination with a computing

mechanism, of a traveling carriage, tabulating mechanism for determining the position of said carriage for different computing zones or columns, manually operable state-controlling means for varying the type of computation carried on by said computing mechanism, means for holding said state-controlling means when set by said manually operable means in a certain condition corresponding to a certain type of computation to be carried on by said computing mechanism, and means operated by said tabulating mechanism for releasing said holding means.

12. The combination with a computing mechanism capable of existing under a plurality of states corresponding to different types of computation, of a traveling element, tabulating mechanism for controlling the movements of said traveling element for different computing zones or columns, said tabulating mechanism including a series of tabulating keys, means for maintaining said computing mechanism in a certain state corresponding to a certain type of computation, and connections universal to said tabulating keys and connected to said maintaining means for manipulating the same to vary the state of said computing mechanism and thus the type of computation carried on thereby at an actuation of any one of said tabulating keys.

13. The combination with a nest of pins, of pin-setting mechanism for said pins, numeral keys for actuating said pin-setting mechanism, said pin-setting mechanism being adjustable to vary the setting action thereof so as to carry on different types of computation, a latch for locking said pin-setting mechanism in a certain position of adjustment, spring means for said setting mechanism normally restrained from action by said latch, a traveling carriage, tabulating mechanism for controlling the movements of said carriage for different computing zones or columns, said tabulating mechanism including a series of decimal keys, and a rail universal to all of said keys and connected to said latch so as to enable the actuation of said spring means on the actuation of any of said tabulating keys to cause a traveling movement of said carriage from one computing zone to another.

14. The combination with a computing mechanism including a series of setting linkages adjustable from an addition setting condition to a subtraction setting condition, of a shifter bar for adjusting said linkages, a latch for said shifter bar, a spring for actuating said shifter bar and the parts connected thereto restrainable by said latch, a traveling carriage, tabulating mechanism for controlling movements of said carriage from one computing zone to another, said tabulating mechanism including a series of

keys, and means universal to said keys for releasing said latch at the actuation of any of said keys.

15. In a combined typewriting and computing machine, the combination with typewriting mechanism including a traveling carriage and tabulating mechanism for controlling different positions of said carriage, of computing mechanism, numeral-printing keys for controlling said computing mechanism, manually operable state-controlling mechanism for said computing mechanism, and means acting jointly with said tabulating mechanism to determine whether on tabulating to any predetermined column the operative is free to write and compute in that column, or whether the operative must change the state of the computing mechanism at that column.

16. The combination with a computing mechanism, of numeral keys for controlling the action of said computing mechanism, a traveling carriage movable to different definite computing zones, said computing mechanism being capable of existing under a plurality of states corresponding to the different types of computation carried on thereby, locking means for said numeral keys, and connections controlled from said carriage during the movements thereof from one computing zone to another for bringing automatically into play said locking means when a change in the state of said computing mechanism is required to correspond with a new type of computation to be carried on in a new computing zone.

17. The combination with a computing mechanism, of numeral keys for controlling the action of said computing mechanism, a traveling carriage movable to different definite computing zones, said computing mechanism being capable of existing under a plurality of states corresponding to the different types of computation carried on thereby, locking means for said numeral keys, connections controlled from said carriage during the movements thereof from one computing zone to another for automatically bringing into play said locking means when a change in the state of said computing mechanism is required to correspond with a new type of computation to be carried on in a new computing zone, and means for concomitantly releasing said locking means and changing the state of said computing mechanism.

18. The combination with a computing mechanism, of a state-controlling mechanism for said computing mechanism, a series of numeral keys for controlling the action of said computing mechanism, a traveling carriage, locking means for said numeral keys, connections between said carriage and said locking means for automatically operating the latter from the former

to lock said numeral keys when a change in state of said computing mechanism is necessary to perform a change in the type of computation carried on in a new computing zone or column determined by said carriage during its movement, and connections between said state-controlling means and said locking means for releasing said locking means at a changing of the state of said computing mechanism.

19. The combination with a computing mechanism, of means for setting said computing mechanism for subtraction, a series of numeral keys for controlling the action of said computing mechanism, a traveling carriage, locking means for said numeral keys, connections bringing said locking means automatically into play at the arrival of said carriage into a subtraction computing column or zone, and connections between said locking means and said subtraction-setting means for concomitantly releasing said locking means with the setting of said computing mechanism for subtraction.

20. The combination with a computing mechanism, of means for setting said computing mechanism for subtraction, a series of numeral keys for controlling the action of said computing mechanism, a traveling carriage, tabulating mechanism therefor, locking means for said numeral keys, connections controlled by a part of said tabulating mechanism for bringing said locking means into play at the arrival of said carriage into a subtraction computing column or zone, connections between said locking means and said subtraction-setting means for concomitantly releasing said locking means with the setting of said computing mechanism for subtraction, tabulating mechanism for determining the computing zones or columns of said carriage, and means operated by said tabulating mechanism for reverting the state of said computing mechanism to an adding state after a subtracting action has been completed in one zone or column and the carriage has been advanced by an actuation of said tabulating mechanism to another computing zone or column.

21. In a combined typewriting and computing machine, the combination with typewriting mechanism, including a traveling carriage, of computing mechanism, numeral keys for controlling the action of said carriage and computing mechanism, locking means for said numeral keys, restraining means for said locking means, state-controlling mechanism for said computing mechanism, manually operable at any zone as determined by said carriage, for changing the state of said computing mechanism, and means brought into action by said carriage on reaching a predetermined zone for releasing said restraining means, to thereby bring said locking means into play to lock

said keys, to indicate to the operative that a change in state is necessary.

22. The combination with typewriting mechanism including a carriage, of computing mechanism, numeral keys for controlling the action of said computing mechanism, locking means for said numeral keys, restraining means for said locking means, means for releasing said restraining means 5 brought into action, under control of said carriage, at predetermined positions thereof to bring said locking means into play to lock said numeral keys, manual means operable at will for changing the state of said computing mechanism to change the type of computation carried on thereby, and means actuated by said state-changing means to release said locking means and permit a further actuation of said computing mechanism by said numeral keys for a new state 10 of said computing mechanism.

23. In a combined typewriting and computing machine, the combination with typewriting mechanism, including a traveling carriage, of tabulating mechanism to control different columnar positions of said carriage, computing mechanism, state-controlling mechanism for said computing mechanism free to be operated at will in any 15 zone or column as determined by the position of said carriage, and means obliging a manipulation of said state-controlling mechanism in a particular computing zone or zones where computation is to be performed, as determined by said tabulating mechanism.

24. In a combined typewriting and computing machine, the combination with typewriting mechanism, including a carriage, and tabulating mechanism therefor, of computing mechanism, column stops for said carriage, forming part of said tabulating mechanism and capable of being set in one position or another, numeral keys for said 20 computing mechanism, state-controlling mechanism therefor, means controlled by one of said column stops when the carriage reaches a particular zone or column for obliging the operative to change the state 25 by locking the numeral keys, and means called into action on tabulating to another zone or column for restoring the state-controlling mechanism to its previous condition or for again locking the keys, depending upon whether said second stop is in one position or another.

25. The combination with a computing mechanism having parts adjustable to change from adding to subtracting, of a subtraction rod, a pin on said rod, a thrust link, a cam on said thrust link engaging said pin to move said rod, and a subtraction key connected to actuate said thrust link.

26. The combination with a computing 60 mechanism, of a series of numeral keys for

controlling the action of said computing mechanism, locking means for said numeral keys, a traveling carriage, a series of tappets carried by said carriage, each having a long leg and a short leg, some of said long legs 70 being uppermost and some undermost, and tripping means actuated by the undermost long legs for bringing said locking means into play.

27. The combination with a computing 75 mechanism, of a series of numeral keys for controlling the action of said computing mechanism, locking means for said numeral keys, a traveling carriage, a series of tappets carried by said carriage, each having 80 a long leg and a short leg, some of said long legs being uppermost and some lowermost, tripping means actuated by the lowermost long legs for bringing said locking means into play, a subtraction-setting mechanism 85 for said computing mechanism, and means for actuating said subtraction-setting mechanism and releasing said locking means.

28. In a combined typewriting and computing machine, the combination with 90 numeral keys and computing wheels, of means whereby said keys cause said wheels to either add or subtract, a latch for holding said means at subtracting position, tabulating keys, and a universal bar operated 95 by said tabulating keys for releasing said latch.

29. In a combined typewriting and computing machine, the combination with 100 numeral keys and computing wheels, of settable means operable at will whereby said keys cause said wheels to either add or subtract, a latch for holding said settable means at subtracting position, tabulating keys, a universal bar operated by said tabulating keys for releasing said latch, a locking device for said numeral keys, means controlled by said tabulating keys for controlling said locking device, and means for making said locking device ineffective by the 105 setting of said settable means for subtraction.

30. In a combined typewriting and computing machine, the combination with typewriting mechanism, including a traveling 115 carriage and tabulating mechanism for controlling the positions of said carriage, of computing mechanism, numeral keys for controlling said computing mechanism, a subtraction key for changing the computation carried on by said computing mechanism, means acting jointly with said tabulating mechanism for locking said numeral keys on tabulating to certain predetermined zones or columns, to warn the operative that 120 said subtraction key should be operated, and means operated by said subtraction key for releasing said locking means.

31. In a computing machine, the combination, with computing mechanism, and nu- 130

5 numeral keys for controlling the action thereof; of mechanism for setting said computing mechanism for subtraction comprising a setting bar, a subtraction key, a thrust link connected to be actuated by said key, and coöperating devices on said thrust link and said bar for operating the latter when the former is actuated.

10 32. In a computing machine, the combination, with computing mechanism, and numeral keys for controlling the action thereof; of mechanism for setting said computing mechanism for subtraction comprising a setting bar, a subtraction key, a thrust link connected to be actuated by said key, a cam on said thrust link, and a projection on said bar engageable by said cam for operating said bar when said link is actuated.

15 33. In a computing machine, the combination, with computing mechanism, and numeral keys for controlling the action thereof; of mechanism for setting said computing mechanism for subtraction comprising an endwise-movable setting bar, a subtraction key located thereabove, a depending thrust link pivoted to said key to be depressed thereby, means for guiding said link during its movements, and coöperating devices on said link and said bar for operating 20 the latter when the former is depressed.

25 34. The combination, with a traveling carriage; of computing mechanism; numeral keys for controlling the action thereof; subtraction-setting mechanism for said computing mechanism; a key for operating said setting mechanism; means for holding said setting mechanism in operated or set position; tabulating mechanism for positioning said 30

carriage; and means actuated by said tabulating mechanism for releasing said holding means.

35 35. The combination, with a traveling carriage; of computing mechanism; numeral keys for controlling the action thereof; mechanism associated with said computing mechanism for setting the same for complementary subtraction; a key for operating said setting mechanism; means for holding said setting mechanism in operated or set position; tabulating mechanism for positioning said carriage; and means actuated by said tabulating mechanism for releasing said holding means.

40 36. In a combined typewriting and computing machine, the combination with type-writing mechanism, including a carriage, of tabulating mechanism for said carriage, including column stops and tabulating keys, computing mechanism, numeral keys for controlling said computing mechanism, state-controlling mechanism for said computing mechanism, manually settable at will in any computing zone or column, and held in the set position, means brought into action by any of said column stops when said carriage reaches a predetermined zone or column for locking said numeral keys, means brought into action on movement of said state-controlling mechanism for releasing said keys, and means brought into action on operation 45 of any tabulating key for releasing said state-controlling mechanism.
